UNITED STATES PATENT OFFICE.

NICOLAS KRIEBS, OF DUNDEE, ILLINOIS.

BATTERY-LAMP.

1,168,892.

Specification of Letters Patent: Patented Jan. 18, 1916.

Application filed May 10, 1915. Serial No. 26,945.

To all whom it may concern:

Be it known that I, NICOLAS KRIEBS, a citizen of the United States, residing at Dundee, in the county of Kane and State of Illinois, have invented certain new and useful Improvements in Battery-Lamps, of which the following is a specification.

This invention relates to improvements in battery lamps or lanterns, and it consists in certain peculiarities of the construction, novel arrangement and operation of the various parts thereof, as will be hereinafter more fully set forth and specifically claimed.

The principal object of the invention is to provide a lamp or lantern, in which the ordinary dry batteries can be used for producing light, and which shall be simple and inexpensive in construction, strong, durable, and efficient in operation, easily handled, either as a lamp or lantern, and so made, that the rays of light furnished thereby can be directed in various directions without changing the position of the body of the lamp.

Another object of the invention is to furnish a lamp of the above named general character, in which one or more dry battery cells can be employed, so as to furnish a greater or less volume of light, or a lamp of low or high power.

Other objects and advantages of the invention will be disclosed in the subjoined description and explanation.

In the accompanying drawing, which serves to illustrate an embodiment of the invention—Figure 1 is a view in side elevation of a lamp or lantern embodying my invention. Fig. 2 is a vertically sectional view thereof, taken on line 2, 2, of Fig. 1, looking in the direction indicated by the arrows. Fig. 3 is an enlarged sectional view taken on line 3, 3, of Fig. 1 looking in the direction indicated by the arrows, showing the construction of the rotary support for the lamp, whereby the position of the latter may be changed so as to direct the rays of light in different directions. Fig. 4 is a similar view to that shown in Fig. 2, but illustrating a modified form of the lamp, and Fig. 5 is a detached perspective view of the bolt which carries the rotary support for the lamp.

Like numerals of reference, refer to corresponding parts throughout the different views of the drawings.

The reference numeral 10 designates a

container for the dry battery cell or cells, and said container is by preference cylindrical in shape and made of metal, and may have attached to its wall a handle 11 to be used for carrying the device or directing the rays of the light from the lamp, mainly, in a horizontal direction. Pivotally secured to the upper portion of the walls of the container 10, and diametrically opposite each other, are the ends 12 of the bail or handle 13, which can be used for carrying the device as a lantern. The lower end of the container is closed as shown in Figs. 2 and 4 of the drawing, and the upper end thereof is closed by means of a cap or cover 14, which is snugly fitted to said upper end of the container. Mounted on the upper surface of the cap or cover 14 at a suitable distance apart, are a pair of upright standards 15 and 16 which are made of metal and said standard 16 has in its upper portion an opening 17 for the reception of one end of a bolt or rod 18, used for the purpose to be presently explained. The upper portion of the standard 15 has in its upper portion an opening 19, into which projects through a suitable opening 20 near one end of a metal bracket 21, a pin 21^a on the block 30, which bracket is connected at its other end to the rear portion of the lamp casing 22, which casing is substantially concavo-convex in shape and has fitted thereon in any suitable manner, a similarly shaped reflector 23, and said casing may have its front end closed by means of a glass plate 24 secured thereon or thereto in an ordinary or any suitable way. The rear or reduced portion of the casing 22 is provided with a hollow neck or extension 25 to receive the lamp socket 26 which is of the ordinary incandescent type and carries a bulb 27, which is located centrally within the reflector 23 and has within same a filament 28 supported on a post or stem 29 extended through the socket 26 as is clearly shown in Fig. 4 of the drawing.

Rotatably mounted between the bracket 21 and the upper portion of the standard 16 is a block of insulating material 30 which is by preference cylindrical in shape, and has on its outer portion, adjacent to the casing 22 a socket 31 in which the extension 25 of the casing 22 is fitted. Extended transversely through the block 30 is an opening 32, for the reception of an adjustable screw 33 which carries on its inner end a spiral

spring 34, which spring has on its free end, a contact piece 35 of metal to contact with the part 29 of the lamp. The screw 33 extends through a transverse opening 36 in the rod or pin 18 which, as shown in Figs. 3 and 5 has on its outer portion a disk 37 to rest between the upper portion of the standard 16 and the adjacent side of the washer 30^a and is electrically connected to the screw 33 and lamp. Adjacent to the disk 37, the block 30 is provided with a reduced portion 38 to fit in an opening in a bracket 39 which is connected to the casing 22 as is clearly shewn in Fig. 3 of the drawings.

15 Referring now to Fig. 2 of the drawings, it will be seen and understood that the container 10 has located therein, one above the other, two battery cells 40 and 41, which may be of the ordinary 1½ volt type and construction. In each of the said cells, the bottom of the carton thereof is removed to expose the zinc bottom of each of the same, to the end that the carbon 42 of the lower cell will contact with the zinc bottom of the upper can or cell and so that the spring 43 or other conductor, interposed between the bottom of the container 10 and the bottom of the lower cell 41 will electrically contact therewith. Leading from the binding post 44 on the upper part of the upper cell 40, is a conductor 45, which is connected to one end of a switch 46 which is insulated from the cap or cover 14 but mounted thereon as is clearly shown in Figs. 2 and 4 of the drawings. This switch 46 may be of any suitable kind, but in the present instance, it is shown as being a spring switch, capable of being depressed into contact with a post 47 mounted on the cover or casing 14, but insulated therefrom. The post 47 has connection through the conductor 48 and a post or screw 49 with the standard 16 as will be readily understood by reference to Figs. 2 and 4 of the drawings.

45 In Fig. 4, is shown a modification in the construction of the lamp, which consists in using a single battery cell 50, instead of a pair of superimposed cells as above described. In this modified construction, the cell 50 is of the ordinary or any preferred construction, and of course, when placed in the container 10, will be insulated therefrom by reason of its covering. In the construction now under consideration, the cell 50 is provided at its upper end with a terminal 44 as in the upper cell of the other construction, which terminal is connected in the similar manner to the switch 46 as above described. The cell 50 has on its upper end another post 51, which is connected by means of a conductor 52, to the standard 15, as will be apparent by reference to Fig. 4 of the drawings.

From the foregoing and by reference to the drawing, it will be readily understood

and clearly seen, that when the construction shown in Fig. 2 is employed, the container 10, by reason of its electrical connections 43 and 42 with the cells 40 and 41 will act as a conductor for one of the poles of the battery and will lead the current through the standard 15 and bracket 21 to the lamp. The other post 44 being connected to the switch 46, will, when said switch is moved into contact with the post 47, complete the circuit through the conductor 48, standard 16, disk 37, rod 18, screw 33 and spring contact 35 with the lamp. By employing two cells, it is apparent that increased voltage will be provided, but it will be understood, that if desired, a single cell instead of two, may be used, and the bottom of said cell exposed to the spring 43 or the like, in electrical contact with the metallic container, when the same results may be obtained, as just above described. Instead of placing the cell in electric contact with the container 10, as above set forth, it is obvious that by using the construction shown in Fig. 4 and above described, satisfactory results will be obtained, yet the voltage will be only one half as much as where two cells are used. It will be noticed by reference to Fig. 4 that the standards 15 and 16 are slightly deflected at their upper portions, which is for the purpose of allowing the lamp casing 22 to be turned downwardly as far as possible without the said standards. As the lamp is rotatably mounted between the standards, it is obvious that it may be turned so as to direct the rays of light in almost any direction. By providing a screw 33 with the spring 34 which carries the contact piece 35, it is manifest that said screw can be adjusted toward or from the lamp socket, and that the action of the spring will always hold the contact piece 35 in contact with the lamp, and in such a manner that the liability of the contact being displaced by vibrations or jolts will be reduced to a minimum.

Having thus fully described my invention what I claim is new and desire to secure by Letters Patent is—

1. In a lamp, the combination with a container having one of its ends open, of a cover for said end, an electric generator located within the container and electrically connected thereto, a pair of spaced apart standards mounted on said cover, a block of insulating material rotatably mounted on and between said standards and having an opening extended transversely therethrough and another opening extended from one of its ends longitudinally therewith and intersecting the first named opening, a pair of lamp carrying brackets mounted on said block, one of said brackets being in electrical contact with one of said standards and the other of said brackets being insulated therefrom, 130

a lamp mounted on the outer portions of said brackets and having a post extended into one end of said transverse opening, a rod or pin extended from one of the standards 5 into the longitudinal opening of said block and having a transverse opening to register with the transverse opening of the block, a screw located in the transverse openings in said block and rod to contact with said post 10 of the lamp, and a circuit closer for the electric generator.

2. In a lamp, the combination with a container having one of its ends open, of a cover for said end, an electric generator 15 within the container and electrically connected thereto, a pair of spaced apart standards mounted on said cover, a block of insulating material rotatably mounted on and between said standards and having an opening 20 extended transversely therethrough and another opening extended from one of its ends longitudinally therewith and intersecting the first named opening, a pair of lamp carrying brackets mounted on said block 25 and extended therefrom, one of said brackets being in electrical contact with one of said standards and the other of said brackets being insulated from the other standard, a lamp mounted on the outer portions of said 30 brackets and having a post extended into one end of said transverse opening, a rod or pin extended from one of the standards into the longitudinal opening of said block and having a transverse opening to register 35 with the transverse opening of the block, a screw located in the transverse openings

in said block and rod, a spring actuated contact interposed between the inner end of said screw and the said post of the lamp, and a circuit closer for the generator.

3. In a lamp, the combination with a container having one of its ends open, of a cover for said end, a pair of battery cells located one on the other within the container and having electrical connection with one 40 another as well as with the container, a pair of spaced apart standards mounted on said cover, a block of insulating material rotatably mounted on and between said standards and having an opening extended transversely therethrough, a pair of lamp carrying brackets mounted on said block and extended therefrom, one of said brackets being in electrical contact with one of said standards and the other of said brackets being insulated from the other of said standards, a lamp mounted on the outer portions of said brackets and having a post at one end of said transverse opening, a journal for one end of said block extended from one 45 of said standards but insulated from the bracket adjacent thereto, a screw located in the transverse opening of said block and electrically connected to said journal, a spring actuated contact interposed between the inner end of said screw and the said post of the lamp, and means to open and close the electric circuit.
